(57) CLAIM

The ornamental design for a front label for camera, as shown and described.

DESCRIPTION

Reference is made to commonly assigned copending applications Serial No. 29/126,362, entitled camera with front and rear labels, filed in the names of Anna C. Schelling, James G. Rydelek, Jeffrey A. Solomon, Walter A. Jakubowski, George A. Xanthos, Anthony F. DiGaetano and Wayne R. Ingalls; Serial No. 29/126,206, entitled rear label for camera, filed in the names of Anna C. Schelling, Wayne R. Ingalls, James G. Rydelek, and Anthony F. DiGaetano; and Serial No. 29/126,191, entitled camera, filed in the names of Anna C. Schelling, James G. Rydelek, Jeffrey A. Solomon, Walter A. Jakubowski and George A. Xanthos. FIG. 1 is a front elevation view of a front label for camera, showing our new design; FIG. 2 is a top plan view thereof; FIG. 3 is a bottom plan view thereof; FIG. 4 is a left-side elevation view thereof; FIG. 5 is a right-side elevation view thereof; and, FIG. 6 is a perspective view thereof, the broken line showing of a camera is for illustrative purposes only and forms no part of the claimed design.
